ISAAC SNOW, OF LAWRENCE, MASSACHUSETTS, ASSIGNOR TO DRAPER CORPORATION,
OF HOPEDALE, MASSACHUSETTS, A CORPORATION OF MAINE.

FEELER MECHANISM FOR LOOMS.

1,392,807.

Specification of Letters Patent.

Patented Oct. 4, 1921.

Application filed October 26, 1920. Serial No. 419,704.

To all whom it may concern:

Be it known that I, ISAAC SNOW, a citizen of the United States, residing at Lawrence, in the county of Essex and State of Massachusetts, have invented an Improvement in Feeler Mechanisms for Looms, of which the following description, in connection with the accompanying drawings, is a specification, like characters on the drawings representing like parts.

This invention relates to feeler mechanisms for looms whereby the filling is replenished without stopping the loom when that in the active shuttle has become nearly exhausted.

The present invention is more directly concerned with that type of feeler mechanism wherein the feeler is supported for movement longitudinally of the shuttle to effect replenishment of filling when, on a detecting beat, the filling is substantially exhausted. In this general type of feeler mechanism, it will sometimes happen that the feeler will detect substantial exhaustion of the filling in the shuttle on a detecting beat, but owing to the contact pressure of the feeler and filling carrier, and other causes, the feeler will fail to respond to the forces tending to move it longitudinally of the shuttle and fail to call for a replenishment of filling, even though the filling in the shuttle is in condition to demand replenishment. In addition to the causes that may operate to objectionably influence the operation of the feeler in the respects noted, is the fact that the filling carriers or bobbins become more or less injured in use, or the surfaces thereof become sticky and act with sufficient retarding effect upon the feeler to prevent its calling a change on a detecting beat when the filling is nearly exhausted.

An important feature of the present invention, therefore, consists of means for relieving the pressure of the feeler against the filling carrier when the filling is nearly exhausted on a detecting beat, to thereby facilitate and insure the movement of the feeler in a direction longitudinally of the shuttle to effect replenishment.

In the present instance of the invention, the feeler is shown as of the "inclined" type, that is, it is shown as supported to enter the shuttle in a direction inclined to the longitudinal axis of the shuttle on a detecting

beat; but in certain aspects the invention is 55 equally applicable to other types of feelers.

In carrying the invention into practical effect, the present instance shows a feeler of the inclined type having mounted thereon a pressure relief device which enters the shuttle on a detecting beat and engages the filling. The pressure relief device has its filling engaging end preferably provided with teeth which, when the filling has become substantially exhausted and the feeler is to be 65 moved longitudinally of the shuttle to call the change, engages the few turns of filling which remain upon the filling carrier as waste, and hold the toothed end of the pressure device from movement, the construction 70 being such that the pressure relief device acts as a lever or pry to relieve the pressure of the end of the feeler against the filling carrier and facilitate its movement longitudinally of the shuttle.

Other features of the invention in addition to the above, will hereinafter be described in connection with the present drawings, which show one good, practical form of the invention.

In the drawings:—

Figure 1 is a perspective view of the detecting side of the loom, showing more particularly the feeler mechanism and associated or coöperating parts;

Fig. 2 is an enlarged plan view, some of the parts being shown in section, illustrating the relation of parts when the shuttle contains a working supply of filling on a detecting beat;

Fig. 3 is a view similar to that of Fig. 2, showing the relation of parts when the filling is substantially exhausted on a detecting beat; and

Fig. 4 is a detached detail showing more 95 particularly in perspective, the rear end portion of the feeler and the pressure device.

In the present instance of the invention, the feeler is shown as of the general type of that illustrated and described in the patent to Edward S. Stimpson, Number 1,309,226, dated July 8, 1919, except as features are modified, as will hereinafter appear; and while the advantages of the present invention are especially observable in 105 connection with the inclined type of feeler illustrated, it is to be understood that it is not necessarily restricted thereto.

Mounted on the loom frame 1 are the brackets 2, one at each side of the loom, and one of which is shown in Fig. 1, in which is mounted for rocking movement the transverse or rock shaft 3 which, as in looms of the replenishing type, controls the actuation of the replenishing mechanism. Since the replenishing mechanism and its control by the transverse or rock shaft 3 is of usual practice, and well known, its description is not here necessary.

Rising from the rock shaft 3 is the arm 4 to which is pivoted at 5 the actuator 6, the rear end portion of which is adapted at 15 times to be engaged by an operating member 7 which may be conveniently provided by the cam follower or a part connected thereto. In the present instance the rear end portion of the actuator 6 has an engaging end 8 carried by a lever 9 pivoted at 10 on the actuator and having a rearwardly-projecting arm 11 which overlies one arm 12 of a bell crank lever pivoted at 13 to a support 14 mounted on the loom frame as 25 at 15. The other arm 16 of the bell crank lever is connected to a transmitter 17 which, as will later appear, is operated to place the end of the actuator 6 in the path of the operating member 7 when the feeler partakes of its movement longitudinally of the shuttle to call for replenishment of filling. As usual in this type of looms, frontward movement of the actuator 6 by the operating member effects rocking movement of 30 the transverse shaft 3 to cause replenishment to be effected.

The lay 18 is provided with the usual shuttle box 19 for the reception of the shuttle 20 in which is mounted the filling 40 carrier or bobbin 21 on which the filling or weft is wound.

The front wall of the shuttle box is provided with an opening 22, and the adjacent wall of the shuttle 20 has an opening 23 45 which is brought into register with the opening 22 when the shuttle is in the detecting box, the construction being such that the feeler may enter the shuttle on a detecting beat and detect the condition of the filling.

Extending from the loom frame is the shipper stand 24, to which is adjustably secured the feeler stand 25 by means of the bolt 26 and slot 27 formed in the feeler 50 stand.

As herein shown, the feeler 28 is of the inclined type, that is, it is supported on the feeler stand to enter the shuttle in a direction inclined to the longitudinal axis thereof, and it is movable toward and from the front of the loom and in a direction longitudinally along the filling carrier. The feeler 28 extends frontwardly through a slotted bracket 29 which may be conveniently formed by upturning the rear edge

portion of the feeler stand. The bracket or flange 29 is provided with a slot 30 through which the feeler extends, and with reference to which the feeler may move laterally or in a direction longitudinally of the shuttle. 70

The frontwardly-extending portion 31 of the feeler is mounted in a rocking bearing 32, in the present instance, which is supported by a bracket 33 on the feeler stand, and a spring 34 is interposed between the bearing 32 and a shouldered portion 35 of the feeler, to normally hold the feeler in its rearward feeling position. 75

The feeler stand is or may be provided with the inclined portion 36 to engage a 80 part connected to the feeler, such as the pin 37 to return the feeler to its proper lateral feeling position when it is returned to its rearward position.

The rear end portion of the feeler 28 is 85 provided with a roughened or toothed portion 38 which, on a detecting beat, engages the filling and sinks into it so that under the frontward pressure exerted against the feeler, the rear end portion of the feeler is 90 held from movement in a direction longitudinally of the shuttle. When, however, the filling is substantially exhausted on a detecting beat, and is no longer able to restrain movement of the feeler in a direction 95 longitudinally of the shuttle, the feeler will tend to move in such direction under the frontward pressure of the filling carrier.

It may happen at times that the feeler will not respond to the forces tending to 100 move it in a direction longitudinally of the shuttle, and the present invention contemplates means to insure movement of the end of the feeler longitudinally of the shuttle when on a detecting beat, the filling is substantially exhausted. In the present instance the invention provides a feeler relief device which acts when the filling is substantially exhausted on a detecting beat, to relieve the pressure between the end of the 110 feeler and the end of the filling carrier, that the feeler may respond to the forces tending to move it in a direction longitudinally of the shuttle, and perforce, effect replenishment of filling. 115

The pressure relief device may be variously contrived, but in the present instance of the invention it comprises a lever 39 which is pivotally connected to the feeler at 40 and has a rearwardly-extending portion 120 provided with the roughened or toothed end 41. The toothed end may be advantageously formed on the arc of a circle, so that as the relief device turns from the position indicated in Fig. 2 to that in Fig. 3, the 125 toothed end portion may remain in engagement with the small amount of filling a still remaining on the filling carrier or bobbin 21. A light spring 42 serves to hold the pressure relief device in its normal position, 130

as indicated in Figs. 2 and 4. In the present instance the spring 42 is conveniently coiled about the pivot 40, and has one end resting against a projection 43 of the pressure relief device, and the other end bearing against the feeler or a lug projecting therefrom as at 44, Fig. 4, the construction being such that normally, and while the loom is running with a working supply of filling, 10 the stop 45 of the pressure relief device is maintained in contact with the side of the feeler.

The transmitter 17, as hereinbefore stated, is connected to the feeler to be operated 15 thereby when the feeler moves in a direction longitudinally of the shuttle, and such connection may be variously contrived. In the present instance the transmitter 17 has a downturned end portion 46 which engages 20 a frontwardly-extending portion 47 of the pressure relief device, the construction being such that when the end of the feeler 28 is moved in a direction longitudinally of the shuttle from the position indicated in 25 Fig. 2 to that indicated in Fig. 3, when the filling is substantially exhausted, the frontwardly-extending portion 47 of the pressure relief device will impart to the transmitter appropriate movement for placing the rear 30 end of the actuator in the path of the operating member, and thereby effect replenishment of filling.

When the loom is running with a working supply of filling in the shuttle, the 35 toothed end portions of the feeler and the pressure relief device both engage the filling, as indicated in Fig. 2, on a detecting beat, and the end of the feeler will be held by the filling from movement in a direction 40 longitudinally of the shuttle by the filling. When, however, the filling is substantially exhausted, and only a small portion remains upon the filling carrier or bobbin 21, as indicated in Fig. 3, the toothed end portion 45 of the feeler will no longer be held by the filling and will start on its longitudinal movement along the filling carrier. The toothed end 41 of the pressure relief device, however, will at such times engage the few 50 turns of filling still remaining on the filling carrier or bobbin, as indicated in Fig. 3, and as the feeler starts on its movement longitudinally of the shuttle, the pressure relief device 39 will be turned upon its pivotal connection with the feeler, and act with a leverage or prying action to relieve the pressure of the filling carrier against the toothed end of the feeler, which may then move more freely in its path longitudinally 55 of the filling carrier. Such relief pressure between the end of the feeler and the filling carrier may be either partial or complete, the latter condition being indicated in Fig. 3, wherein the toothed end of the feeler is 60 shown as having been moved fully from

contact with the filling carrier or bobbin as it moves in a direction longitudinally of the shuttle.

From the construction described, it will be observed that notwithstanding the character of the filling carrier or bobbin surface with reference to which the end of the feeler moves longitudinally to effect call for replenishment of filling, the feeler will be unobstructed in its longitudinal movement. 70 After a call for replenishment of filling in the manner stated, the spring 34 will return the feeler to its rearward position and the pin 37 acting along the cam or incline 36 will move the feeler to its proper lateral position, the parts thereupon resuming their normal position, as indicated in Fig. 1.

What is claimed is:—

1. In a feeler mechanism for looms, the combination of a feeler that is supported in 85 position inclined to the path of the lay and held from movement longitudinally of the shuttle on a detecting beat by engagement with the filling until substantial exhaustion thereof, and means acting to pry the feeler 90 away from the filling carrier as the feeler is moved in a direction longitudinally of the shuttle on a detecting beat and thereby relieve the pressure of the feeler against the filling carrier. 95

2. A feeler mechanism for looms having in combination, a feeler supported for movement toward and from the front of the loom in a path inclined to the longitudinal axis of the shuttle and held from movement 100 along the filling carrier on a detecting beat by engagement with the filling until the filling is nearly exhausted, means for effecting replenishment of filling when the feeler is moved longitudinally of the shuttle on a 105 detecting beat, and means for prying the feeler from engagement with the filling carrier due to movement of the filling carrier longitudinally of the shuttle.

3. A feeler mechanism for looms having 110 in combination, a feeler supported for movement toward and from the front of the loom in a path inclined to the longitudinal axis of the shuttle and held from movement along the filling carrier on a detecting beat 115 by engagement with the filling until the filling is nearly exhausted, means for effecting replenishment of filling when the feeler is moved longitudinally of the shuttle on a 120 detecting beat, and means carried by the feeler for prying the feeler away from engagement with the filling carrier due to the movement of the feeler longitudinally of the shuttle.

4. A loom having a feeler mechanism comprising, in combination, a feeler supported to enter the shuttle in a direction inclined to the longitudinal axis of the filling carrier and movable in a direction inclined to the path of the lay, but held from movement 130

along the filling carrier on a detecting beat by engagement with the filling until approaching exhaustion thereof and then moving longitudinally of the filling carrier, and

5 a pressure relief device which becomes effective by movement of the feeler longitudinally of the shuttle to pry the feeler from engagement with the filling carrier.

5. In a feeler mechanism for looms, the 10 combination of a feeler that is supported for movement longitudinally of the shuttle and is held from such movement by engagement with the filling on a detecting beat until substantial exhaustion of filling, and 15 means operated by movement of the feeler longitudinally along the filling carrier on a detecting beat for relieving the pressure of the feeler against the filling carrier.

6. In a feeler mechanism for looms, the 20 combination of a feeler that is supported to enter the shuttle on a detecting beat and to be moved longitudinally of the shuttle when the filling is substantially exhausted, means for effecting replenishment of filling when 25 the feeler is moved longitudinally of the shuttle on a detecting beat, and a pressure relief lever pivotally mounted on the feeler and acting as the feeler moves longitudinally of the shuttle to pry it from the filling 30 carrier to facilitate the feeler movement.

7. In a feeler mechanism for looms, the 35 combination of a feeler that is supported for movement longitudinally of the shuttle and is held from such movement by engagement with the filling on a detecting beat until substantial exhaustion of filling, and a pressure relief device which engages a 40 surface carried by the lay on every detecting beat and acts to pry the feeler away from the filling carrier when the filling is substantially exhausted.

8. In a feeler mechanism for looms, the 45 combination of a feeler that is supported for movement longitudinally of the shuttle and is held from such movement by engagement with the filling on a detecting beat until substantial exhaustion of filling, and a pressure relief device which enters the shuttle with the feeler on each detecting beat 50 and which is rendered effective by movement of the feeler in a direction longitudinally of the shuttle on a detecting beat for relieving the pressure of the feeler against the filling carrier.

55 9. In a feeler mechanism for looms, the combination of a feeler that is supported for movement toward and from the front of the loom and in a direction longitudinally of the shuttle and is held from move-

ment longitudinally of the shuttle on a detecting beat by engagement with the filling until it is nearly exhausted, a pressure relief device which engages a surface within the shuttle on a detecting beat and relieves the pressure of the feeler against the filling carrier as the feeler is moved longitudinally of the shuttle, and means for effecting replenishment of filling when the feeler is moved longitudinally of the filling carrier on a detecting beat.

10. In a feeler mechanism for looms, the combination of a feeler that is supported for movement toward and from the front of the loom and in a direction longitudinally of the shuttle and is held from movement longitudinally of the shuttle on a detecting beat by engagement with the filling until it is nearly exhausted, a pressure relief device which is pivotally mounted on the feeler and engages a surface within the shuttle on a detecting beat and relieves the pressure of the feeler against the filling carrier as the feeler is moved longitudinally of the shuttle, and means for effecting replenishment of filling when the feeler is moved longitudinally of the filling carrier on a detecting beat.

11. In a feeler mechanism for looms, the combination of a feeler that is supported for movement in a direction longitudinally of the shuttle and is held from such movement on a detecting beat by engagement with the filling, a pressure relief device provided with teeth for engaging the filling in the shuttle on a detecting beat, connections between the feeler and the pressure relief device which become effective to relieve the pressure of the feeler against the filling carrier as the feeler is moved longitudinally of the shuttle on a detecting beat, and means for effecting replenishment of filling.

12. In a feeler mechanism for looms, the combination of a feeler supported for movement in a direction longitudinally of the shuttle and held from such movement by engagement with the filling on a detecting beat until the filling is nearly exhausted, a lever pivotally mounted on the feeler and provided with teeth to engage the filling on a detecting beat and by swinging movement of the lever due to movement of the feeler in a direction longitudinally of the shuttle on a detecting beat to disengage the feeler from contact with the filling carrier.

In testimony whereof, I have signed my name to this specification.

ISAAC SNOW.
